UNITED STATES PATENT OFFICE.

EDMUND ROTH, OF ILLFURT, ALSACE, GERMANY.

BALLOON FOR AIRSHIPS.

1,048,101.

Specification of Letters Patent. Patented Dec. 24, 1912.

Application filed February 24, 1911. Serial No. 610,592.

To all whom it may concern:

Be it known that I, EDMUND ROTH, a subject of the Emperor of Germany, residing at Illfurt, Alsace, Germany, have invented new and useful Improvements in Balloons for Airships, of which the following is a specification.

This invention has reference to a balloon for airships of the non-rigid type. The balloon is divided into a number of chambers in the known manner by cross partitions situated vertically to the longitudinal axis, which chambers communicate with each other for the purpose of equalizing the pressure by means of automatically acting valves, by which arrangement a uniform distribution of the pressure of the gas is obtained in all parts of the balloon thereby considerably protecting the envelop of the balloon, and my invention consists, firstly, in that valves which are coupled together so that they can all be opened simultaneously from outside the balloon are mounted on valve seats in the said partitions and the said seats are rigidly connected to each other, and secondly, in that the balloon proper is surrounded by an outer envelop or jacket intended to be filled with air and forming an outer undivided ballonet which is provided with a single exhaust valve, the said outer envelop being connected with the balloon proper by strips of fabric arranged in non-continuous lengths longitudinally of the balloon and 120° apart. The preferred arrangement of the valves is illustrated in the accompanying drawings, automatic pressure equalizing valves being mounted in slideable boxes which themselves in conjunction with the said pressure equalizing valves constitute valves (hereinafter called box-valves) that are connected to each other and normally held firmly on their seats by springs.

During the filling and emptying of the balloon the box-valves must be opened by hand. This can only be effected when the envelop of the balloon is fully stretched. The actual gas envelop is for this purpose surrounded by an outer envelop maintained at an equal distance everywhere therefrom, which latter envelop before filling as well as during the emptying must be filled with air by means of a pump so that the balloon has the required stretched shape. This air envelop, surrounding the gas balloon on all sides and permitting the manipulation of

the box valves, has furthermore the known advantage of powerfully counteracting the diffusion of the gas, and furthermore provides an excellent protection against heat. The air-jacketing renders the filled balloon very rigid, inasmuch as it constitutes a ballonet completely filled with air surrounding the gas balloon. The air-jacketing completely surrounding the gas balloon and in combination with suitably arranged valves, the working of which is hereinafter described, has the great advantage that any height can be attained whereas according to existing constructions the air-ballonets are calculated for a definite height which cannot be exceeded.

In the drawings:—Figure 1 is a longitudinal section through the body of the balloon. Fig. 2 is a cross section through the same. Fig. 3 is a sectional view of a box valve drawn to a larger scale than Figs. 1 and 2.

The gas balloon *a* is divided into several separate compartments by cross partitions *b* arranged vertically to its longitudinal axis. Each of these partitions *b* has a box valve *c*. The seats of the box-valves are rigidly connected with each other by tubes *d* with wide longitudinal slots. The box valve *c*, shown in section in Fig. 3 comprises a valve disk *e* which has a guide rod *f* on both sides, and is normally held centrally between the seats *h* and *i* by springs *g* acting on both sides. The various chambers normally communicate with each other by the openings in the seats *h* and *i* and the intermediate space situated between the wall *k* and the valve disk *e*. If on the one side there is a superpressure overcoming the tension of the spring *g*, then the valve disk *e* will be pressed on to the oppositely situated seat and will shut off this compartment during the existence of the superpressure. The cylindrical wall *k* connects both the valve-plates *h* and *i* to form a casing in which the valve *e* moves, the whole forming the box-valve *c*. The seat of this box valve is at *l* in an expansion of the tube *d* (Fig. 3). A spring *m* which acts on the guide rod *n* that carries the said box-valve normally holds the valve firmly on its seat.

The filling of the balloon *a* is effected through the pipe connection *s*. The filling of the various compartments can only be effected after the box valve *c* has been withdrawn from its seat *l* by means of a cord *o*.

which is actuated from the car *r* by pulling the cord *q*. As the various valves *c* are connected with each other by a suitable member *p* which is connected on the one hand to the disk *i* and on the other hand to the disk *h*, by pulling the cord *q* all the valves *c* are opened simultaneously and the various compartments can be filled.

The opening of the valves *c* for filling the balloon *a* by pulling the cord *q* can only be effected when the balloon *a* is in its stretched condition. For this purpose the gas balloon *a* is surrounded by a second envelop *t* held everywhere at the same distance from the gas envelop *a* by means of cloth strips *u* arranged in non-continuous lengths longitudinally of the balloon and 120° apart as shown in Fig. 2. The intermediate space between the gas envelop and the envelop *t* is filled with air by means of an air pump *v* provided in the car *r* until the balloon has attained its cylindrical working shape.

The air-jacketing situated between the envelops *a* and *t* is provided with a valve *w* which is automatically opened on the ascension of the balloon so that a portion of the air contained can escape into the outer atmosphere. If the balloon ascends to considerable heights then the gas balloon, which previously in its lower portion *a'* was of the shape indicated in dotted lines in Figs. 1 and 2, will first assume the full cylindrical shape. On the further rising of the balloon the valve *x*, the spring of which is slightly stronger than that of the valve *w*, will be opened, so that a portion of the gas can escape.

The valves *c* and the valve *z* connecting the gas balloon with the outer atmosphere are connected by the traction members *j* through the intermediary of the cords *o* and *y* with the lower portion *a'* of the gas balloon. This connecting member *j* is so regulated that the valves *c* connecting the various chambers and then the valve *z* are opened when the lower envelop *a'* has assumed the full cylindrical shape. By opening the valve *z* a portion of the gas escapes and any danger of the bursting of the balloon envelop *a* is thus avoided.

The emptying of the balloon is effected by

the valve *z*. This valve is opened by means of the cord *y* by pulling on the cord *q* from the car *r*. The pull on the cord *q* for the purpose of emptying the balloon *a* must be considerably greater than when filling, in which case only the box valves *c* are opened. The cord *q* is operated by means of a crank passing over a scale which permits of reading off the effect occasioned by the various positions of the crank.

What I claim as new and desire to secure by Letters Patent is:—

1. In a balloon for airships of the non-rigid type, a plurality of transverse partitions dividing the balloon into a number of compartments, a valve seat in each of the said partitions, rigid connections between the said valve seats, a valve mounted on each of the said seats, means for coupling the said valves together, and means operable from outside the balloon for opening all the said valves simultaneously.

2. In a balloon for airships of the non-rigid type divided by transverse partitions into a plurality of compartments, a valve seat in each of the said partitions, rigid connections between the said valve seats, a compound valve mounted on each of the said seats consisting of a box-like structure formed with apertures in each end and within which an automatic pressure equalizing valve is mounted, means for coupling the said compound valves together, and means operable from outside the balloon for opening all the said valves simultaneously.

3. The combination with a balloon divided transversely into a plurality of compartments by partitions in which valves coupled together and operable from outside the balloon are mounted, of an outer undivided envelop or jacket connected to the balloon by strips of fabric arranged longitudinally of the balloon and 120° apart.

In testimony whereof I have signed my name to this specification in the presence of two subscribing witnesses.

EDMUND ROTH.
